APPARATUS FOR DRESSING THE EDGES OF
THE UPPER LEATHER IN THE MANUFAC-
TURE OF SHOESViktor Bata and Adolf Vitek, Zlin, Czechoslo-
kia, assignors to Bata, národní podnik, Zlin,
CzechoslovakiaApplication January 20, 1948, Serial No. 3,206
In Czechoslovakia January 20, 1947

9 Claims. (Cl. 12—51)

1

The present invention relates to the manufacture of shoes, more particularly to an apparatus for dressing the edges of the upper leather of shoes, especially of shoes which have been tacked by means of nails, small clasps or like fastening means. Heretofore such dressing operation has been carried out by knocking or hammering. The invention is concerned more specifically with the dressing of the toe part of shoes.

In the usual tacking of a shoe toe part on a tacking machine, the stretched upper leather is bent over the edge of a last and that of the inner sole together with the toe cap and the lining, the upper leather being scored by means of a knife in its portion of maximum bend so as to permit better folding of the material and in this bent-over and folded position the upper leather is fastened to the inner sole by means of nails. During such a tacking operation so much material is accumulated especially in the portions of maximum bend, that in view of the next operation to be effected on the shoe, that is securing the sole, it is necessary to distribute evenly the accumulated material or to eliminate the accumulation, and moreover it is necessary to improve the border of the shoe which has been formed in the portions where the upper has been bent over the inner sole and to smooth the creases formed at the edges of the upper due to the folding of the material. According to former proposals, all those imperfections in tacking have been eliminated on hammering or knocking machines, both of the hand operated and the automatic types, which by the effect of impacts produced by hammering rings mounted on a rotating drum draw the material additionally over the edge of the inner sole so as to eliminate the creases, make the border sharper and smooth the material unduly accumulated at the bend of the shoe toe part. In many cases it becomes even necessary to remove the accumulated material by cutting off the same. The hammering on a hand operated hammering machine is one of the most difficult operations in the manufacture of shoes. The effort may be reduced to a certain extent by the use of a hammering machine in which the shoe is automatically held and fed to the hammering drum, but such a machine does not comply fully with the requirements of modern production because it represents the main source of noise in a shoemaker's shop.

An object of the apparatus in accordance with the present invention is to eliminate the toil connected with, and the noise of the hammering operation while obtaining a clean and sharp edge

2

on the shoe, an appropriate final stretching of the material and a distribution and pressing of all the unduly accumulated material.

The essence of the invention consists in this that instead of the hammering operation as heretofore carried out, the shoe after the tacking operation is subjected to a continuous and noiseless pressing operation by which the tacked upper is subjected to final stretching over the edge of the last and that of the inner sole and the material accumulated in the toe part is distributed by the pressure, any imperfectly driven tacking nails being forced at the same time into the inner sole. A convenient form of apparatus for carrying out the above method comprises a two part mould, the parts of the latter being slideable relatively to each other, and a heel support which forces the tacked shoe between the mould parts. Preferably both mould parts are heated so that the pressing operation is effected in heated condition whereby partial ironing of the material takes place. Such ironing has been effected heretofore by hand upon completion of the hammering operation. Moreover the scratching or removing the surplus material in any other manner and thus any depreciation of the material are completely avoided.

In addition to the ease and noiselessness of the operation and the high quality of the work, another advantage consists in this that the operation may be effected by unskilled persons, the products are all uniformly pressed, whereby their fastening to the sole is made easier, and—last but not least—the output is increased.

Further advantages and features of the present invention will appear from the following description when read in connection with the accompanying drawings, in which:

Fig. 1 shows diagrammatically a two pair station in elevation;

Fig. 2 is a side elevation of a station in its initial position; and

Fig. 3 is a side elevation of a station in its operative position.

With reference to the drawings, a base plate 1 is provided having secured thereon two casings 2, 2 for the left and right press mould, respectively. Each mould comprises a fixed lower part 3 and a slideable upper part 4, the latter being held in the casing 2 by means of screws 6 and nuts 5. The screws 6 are screwed into the upper mould part 4 and pass through longitudinal slots 7 in the casing 2. The slideable upper part 4 of the mould has a cavity 8 corresponding in shape to that of the shoe toe part, while the fixed mould part 3 has a recess 9 corresponding to the

underside of the shoe. In the recess 9 a number of grooves 10 are formed being directed towards the axis of the last (Fig. 1); the object of the grooves is to draw the material under treatment towards the axis of the last. A heating element 11 is mounted in the body of the lower mould part 3 and serves for heating the mould.

Another important element of the arrangement is the heel support 12 which is provided with the removable washer 13.

The heel support 12 and the slidable upper mould part 4 are operated e. g. by means of a hand lever 14 fastened on a shaft 15 which is mounted on the base plate 1. Fast on the shaft 15 is a fork 16 which by means of a pin 17 is connected to a link 18 freely rotatable about a pin 19. The pin 19 is supported rotatably by two levers 20 which are mounted pivotably on a pin 21 secured on the base plate 1. From the pin 19 are suspended two links 22 having their opposite ends mounted on a pin 23 carried by the heel support 12. In addition the heel support 12 is pivoted to a pin 24 to which it is connected by a lever 25, also through the intermediary of the pivot pin 23. The pin 24 is mounted on the base plate 1. From the pivotal movement of the lever 25 about the pin 24 the return movement of the upper mould part 4 is derived through links 26 which by their one end are mounted on pins 27 provided in the upper mould part 4 while their lower ends pass freely over a pin 28 and are provided with nuts 29. The pin 28 is freely rotatable in a sleeve 30 fastened to the lever 25. The pressing movement of the upper mould part 4 is derived directly from the heel support 12 by means of the shoe 31 which is inserted into the mould in a manner to be disclosed hereinafter.

The apparatus so far described is operated in the following manner:

In the position shown in Fig. 1 the left mould is under pressure and the right mould is in its initial position which is shown also in Fig. 2. The operator inserts loosely a last 31 carrying the tacked shoe into the cavity 8 of the slidable upper mould part 4, toe foremost, the heel support being sufficiently remote from the heel of the last, as shown in Fig. 2, as not to be in the way of the last. The hand lever 14 is in its elevated position, and the operator, while retaining the shoe by his left hand in the mould cavity, draws by his right hand the lever 14 down in the direction S₁. This movement causes the lever 16 to swing in the direction S₂, and through the effect of the link 18 the pin 19 on the levers 20 is raised about the pin 21 in the direction S₃. During the upward movement of the pin 19 the links 22 are moving up and entrain the heel support 12 which with its washer 13 comes to bear firmly against the heel of the shoe 31 and thus first forces the shoe into the cavity 8 of the projecting upper mould part 4, as shown in Fig. 2, and then begins to force the upper mould part into the interior of the casing 2. During this movement the lower toe part is caused to engage into the recess 9 of the fixed mould part 3, with simultaneous forming, smoothing and pressing of the tacked toe part of the upper. At this stage the grooves 10 aid in giving the pressed material a correct final stretch towards the axis of the last. The end position of the lever system and of the mould and shoe upon termination of the pressing operation is shown in Fig. 3. The shoe is retained in this position within the heated mould until the operator has changed the shoe in the adjacent mould. The last mentioned mould,

which up to this moment has occupied the position shown in Fig. 3, is returned by movement of the lever 14 in counterclockwise direction to its initial position shown in Fig. 2, the reverse pivotal movement of the heel support 12 about the pin 24 causing the pin 28 to bear against the nuts 29 and to withdraw by means of the links 26 the mould part 4 from the casing 2. In this manner the shoe is released, and when all the parts have been returned to the position shown in Fig. 2, the operator removes the shoe from the machine and inserts a fresh shoe in place thereof. Thus the operations proceed alternately in the adjacent moulds.

It should be noted that during the final pressing in the mould any nails, clasps or the like, which still are not completely driven in the inner sole, are forced into the latter so that the shoe removed from the press mould has its pressed part perfectly smooth. The operation of the machine is quite noiseless, even if the hand drive is replaced by a hydraulic or other motor drive. This latter arrangement is also comprised within the scope of the present invention.

What we claim is:

1. An apparatus for dressing the edges of the upper leather in the manufacture of shoes, comprising a two part mould having its parts arranged slidably relative to each other, and a heel support adapted to force a tacked shoe between the two mould parts.

2. An apparatus for dressing the edges of the upper leather in the manufacture of shoes, comprising a two part mould of which the lower part is adapted to engage the tacked portion of the shoe, is fixed while the upper mould part is slidable in a guide, and a heel support adapted to force a tacked shoe between the two mould parts.

3. An apparatus for dressing the edges of the upper leather in the manufacture of shoes, comprising a fixed lower mould part adapted to engage the tacked portion of a shoe, an upper mould part slidable in a guide provided in a casing in which both mould parts are housed, and a heel support adapted to force a tacked shoe between the two mould parts.

4. An apparatus for dressing the edges of the upper leather in the manufacture of shoes, comprising a fixed lower mould part adapted to engage the tacked portion of the shoe, a slidable upper mould part, a heel support adapted to force a tacked shoe between the two mould parts, and grooves provided in the cavity of the fixed lower mould part and directed towards the axis of the last and mould to impart a final stretching to the pressed material.

5. An apparatus for dressing the edges of the upper leather in the manufacture of shoes, comprising a fixed lower mould part, a slidable upper mould part, a heel support adapted to force a tacked shoe between the two mould parts, grooves provided in the cavity of the fixed lower mould part and directed towards the axis of the last and mould to impart a final stretching to the pressed material, and a heating device in that part of the mould which engages the tacked edge of the upper.

6. An apparatus for dressing the edges of the upper leather in the manufacture of shoes, comprising a fixed lower mould part, a slidable upper mould part, a heel support adapted to force a tacked shoe between the two mould parts and mounted on a pivoted lever, grooves provided in the cavity of the fixed lower mould part and directed towards the axis of the last and mould.

to impart a final stretching to the pressed material, and a heating device in that part of the mould which engages the tacked edge of the upper.

7. An apparatus as set forth in claim 6, wherein the heel support is controlled by a hand lever through the intermediary of a lever system.

8. An apparatus for dressing the edges of the upper leather in the manufacture of shoes, comprising a fixed lower mould part, a slideable upper mould part, a heel support adapted to force a tacked shoe between the two mould parts, grooves provided in the cavity of the fixed lower mould part and directed towards the axis of the last and mould to impart a final stretching to the pressed material, and a heating device in that part of the mould which engages with the tacked edge of the upper, the slideable upper mould part being forced into operative position by the heel support through the intermediary of the shoe carried on the latter.

9. An apparatus for dressing the edges of the upper leather in the manufacture of shoes, comprising a fixed lower mould part, a slideable upper mould part, a heel support adapted to force a tacked shoe between the two mould parts and

5

10 mounted on a pivoted lever, grooves provided in the cavity of the fixed lower mould part and directed towards the axis of the last and mould to impart a final stretching to the pressed material, and a heating device in that part of the mould which engages with the tacked edge of the upper, the slideable upper mould part being forced into operative position by the heel support through the intermediary of the shoe carried on the latter, the return movement of the upper mould part from its operative position being controlled by a link system.
